[57] **ABSTRACT**

An electrical switch including an operating member pivotally mounted on a body and carrying a spigot which extends towards the base of the body, on which the fixed contacts are positioned. A movable contact member slidable on the base includes a pair of resiliently electrically interconnected parts engageable with the fixed contacts, the contact member being engaged with the spigot. A compression spring surrounds the spigot and urges the contact member into engagement with the base, the compression spring acting as part of an over-center mechanism.

ELECTRICAL SWITCHES HAVING IMPROVED
CONTACT STRUCTURE

This invention relates to electrical switches.

A switch according to the invention comprises, a body having a base, a plurality of fixed contacts carried by the base and insulated from one another, an operating member pivotally mounted on the body, a spigot carried by the operating member, the spigot extending towards the base, a movable contact member slideable on the base and including a pair of resilient electrically interconnected parts engageable with the fixed contacts, said contact member being engaged with said spigot, and a compression spring surrounding said spigot and urging said contact member into engagement with the base, the arrangement being such that pivotal movement of the operating member relative to the body is transmitted by said spigot to the contact member to cause said contact member to slide relative to the base, said spring acting as part of an over-center mechanism urging the movable contact member and the operating member to one side or the other of a central position.

One example of the invention is illustrated in the accompanying drawings, wherein

FIG. 1 is a sectional view of an electrical switch, and

FIG. 2 is a plan view of the movable contact member of the switch shown in FIG. 1.

Referring to the drawings, the switch includes a hollow molded synthetic resin body 11 which is open at one end, and which is closed at the other end by an integral base 12. Set in the base 12, and flush with the inner surface of the base are a plurality of fixed contacts 13 each of which is electrically connected to a respective blade connector on the exterior of the base. Upstanding from opposite sidewalls of the body 11 are a pair of lugs 14 (one of which is shown in FIG. 1) and extending between the lugs 14 and pivotally mounted thereon is a molded synthetic resin, rocker-type operating member 15. Integral with the operating member 15 and extending towards the base 12 is a cylindrical spigot 16 which is engaged at its free end with a movable contact member 17. The movable contact member 17 is stamped from a strip of phosphor bronze, and is generally H-shaped. The limbs 18 of the H-shaped member 17 are curved downwardly out of the plane of the remainder of the member 17, and define independently resilient arms engaging the base 12. The central portion of the member 17 is formed with an elongated slot 19 through which the free end of the spigot 16 extends, and the contact member 17 is urged firmly into engagement with the inner surface of the base 12 by a compression spring 21 which surrounds the spigot 16 and which acts between the operating member 15 and the contact member 17. It will be noted that the material of the member 17 is chosen to impart resilience to the arms. Copper, which is commonly used for contacts, is not suitable for this purpose.

The fixed contacts 13 are arranged in pairs, only one of each pair being shown in the drawings. The contacts in each pair of contacts are positioned side by side, and are spaced apart by a distance equal to the width of the contact member 17. Thus, when one of the contacts 13 of a pair of contacts is

engaged by one of the limbs 18 of the movable contact member 17, then the other contact of that pair will be engaged by a further limb 18 of the contact member 17 and the two contacts of the pair will be electrically interconnected through the contact member 17. The position of the contact 13 on the base 12 will be dependent upon the intended function of the switch, and clearly, since the member 17 has four limbs, then four fixed contacts can be electrically interconnected simultaneously. FIG. 1 shows the switch in a position wherein the contact member 17 is bridging the extreme right-hand pair of contacts 13, and by pivoting the operating member 15 in a clockwise direction, as shown in the drawings, the member 17 can be moved to the left, to bridge the extreme left-hand pair of contacts and the central pair of contacts simultaneously, so that all four contacts would be electrically connected.

When the operating member 15 is pivoted relative to the body 11, the spigot 16, which extends through the slot 19 in the member 17 engages one end of the slot 19, and thereafter the member 17 is moved with the spigot 16 the member 17 sliding on the base 12, and remaining substantially parallel with the base 12. The spring 21 will be stressed to the greatest extent when the spigot 16 is at right angles to the base 12, and so the spring 21 serves to bias the operating member to one side or the other of the central position wherein the spigot 16 is at right angles to the base 12. Thus, during movement of the operating member 15 to move the contact member 17 from one end of the base to the other, initially resistance will be felt to the movement of the operating member, as the spigot approaches the position wherein it is at right angles to the base, and subsequently, when the spigot 16 has moved beyond the central position, then the spring 21 will aid the pivoting movement of the operating member 15.

The end walls of the body 11 of the switch are formed with respective, resilient lugs 22 by means of which the switch can be engaged as a snap fit in an aperture in a mounting plate. It will be appreciated that the spigot 16 need not be cylindrical and could, for example, be of rectangular cross section.

Having thus described my invention what I claim as new and desire to secure by Letters Patent is:

1. An electrical switch comprising a body having a base a plurality of fixed contacts carried by the base and insulated from one another, an operating member pivotally mounted on the body, a spigot carried by the operating member, the spigot extending towards the base, a movable contact member slideable on the base and defined by a conductive strip having a hole therein through which said spigot passes, and including a pair of integral resilient electrically interconnected parts engageable with the fixed contacts, and a compression spring surrounding said spigot and urging said contact member into engagement with the base, the arrangement being such that pivotal movement of the operating member relative to the body is transmitted by said spigot to the contact member to cause said contact member to slide relative to the base, said spring acting as part of an overcenter mechanism urging the contact member and the operating member to one side or the other of a central position.

2. A switch as claimed in claim 1 in which the strip is H-shaped to define four independently resilient contacts.
